UNITED STATES PATENT OFFICE.

EDWARD G. ROWLEY, OF BELLEVILLE, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed June 30, 1926. Serial No. 119,542.

This invention relates to sound-deadening casings for typewriting machines, especially those of the "portable" class, and more particularly to novel means for controlling the movements of the paper-carriage and for line-spacing the work-sheets.

The machine is enclosed in a felt-lined casing having a displaceable cover with a glass sealed sight opening; the front wall of the casing having an opening through which the keyboard protrudes.

The carriage may be returned after each line of typing by means of an exterior handle pivoted upon the casing at one side of the keyboard. The handle extends to the interior of the casing, to revolve an interior pinion and drum, the latter having a cord, one end of which is fast to the line-space lever acting upon the platen, so that, without opening the cover, the platen may be returned to begin a new line, and at the same operation it may be automatically line-spaced.

It is often desired to line-space the work-sheet without opening the cover, while the carriage is at different points in its range of travel, or in other words while the carriage remains stationary at any point. Heretofore, the cover has been opened for this operation, and the rotation of the platen has been thereupon effected by means of a finger-wheel, which is slow. According to one of the features of this invention, the space-bar at the keyboard of the typewriter may be held down for the purpose of locking the carriage against movement. At the same time said handle may be operated, and the line-spacing lever of the typewriter may be vibrated as many times as desired, to rotate the platen to the required extent, without moving the carriage, and without opening the cover.

Another feature of this invention relates to novel means at the exterior of the casing for releasing the carriage in order to permit the unobstructed control thereof by means of said carriage-return handle, for both advance and return travel of the carriage. To this end, there is provided a depressible button at one side of the keyboard, which is effective by means of a special linkage to disconnect the letter-spacing rack from its associated escapement wheel.

It will be understood that the return spring with which the line-spacing lever is

provided is made stronger than usual, to permit the movement of the carriage without line-spacing the work-sheet. Ordinarily, however, it is desired to return the carriage and to line-space the work-sheet all in one operation, and, in this case, upon reaching the end of the return stroke of the carriage, as determined by the marginal stop, the line-spacing lever spring will yield under the direct pull of its operating cord, to swing the handle and line-space the work-sheet.

Provision is made for the complete manipulation of the carriage from the outside of the casing to thereby render the displacement of the cover unnecessary except to replace the work-sheet.

Other features and advantages will hereinafter appear.

In the accompanying drawings, Figure 1 is a plan of the sound-deadening casing, with the cover removed, showing the typewriter placed therein, and all the operating mechanism.

Figure 2 is a perspective, showing the means for releasing the letter-spacing rack and also the means for locking the letter-spacing wheel.

Figure 3 is a fragmentary perspective, showing the letter-spacing wheel in its locked position.

Figure 4 is a longitudinal cross-section in elevation, showing the carriage-return drum and means for releasing the carriage.

Figure 5 is a cross-section through line 5-5 of Figure 1.

The Underwood four row portable machine is provided with a traveling carriage 10, upon which a platen 11 is rotatably mounted by means of a shaft 12. The platen is struck at the front thereof by type-bars 13, which are swung upon depression of keys 14. At each key depression, the carriage is letter-spaced by means of a universal bar and other mechanism, not shown, but acting upon an escapement wheel 15, which is operatively connected to the carriage by means of a pinion 16 and a rack 17. The carriage is slidably mounted on anti-friction bearings 18, sliding on tracks 19 supported by a frame 20.

To return the carriage from the outside of the casing, there is provided a handle 21 pivotally mounted on a shaft 22, supported on a bracket 23, fast by means of screws 24

to a baseboard 25. Said handle forms an integral part of a sector 26, which is swung on the shaft 22 upon depression of the handle, and engages with a pinion 27 fast to a shaft 28 rotatably mounted on the bracket 23. The shaft 28 carries a drum 29 fast thereto, upon which a cord 30 is wound. One end of the cord is fast to the drum, while the other end is fast to a line-spacing lever 31 by means of an extension 32. The line-space lever 31 is operatively connected, by means of a pawl 33, to a line-space wheel 34. With this arrangement not only is the carriage returned, upon depression of the handle 21, but the platen is also line-spaced.

In order that the carriage may be positioned to the printing point, there is provided a scale 35, which co-operates with a pointer 36 carried by the handle 21. There is also provided mechanism for swinging the rack 17 out of engagement with the pinion 16. Said mechanism may include a button 37 mounted at the end of a shaft 38, which shaft is slidably mounted on the front wall 25 of the casing and actuates a bell-crank 39 mounted on a support 40 by means of a shoulder-screw 41. The bell-crank 39 carries a link 42 pivotally mounted thereon, which link extends sidewardly and is operatively connected to a lever 43. Said lever is supported by a bracket 44 and is pivotally mounted on a stud 45 fast to the bracket, the bracket in turn being fast to a lower extension of the track 19 by means of rivets 46. The lever 43 carries a roller 47 at one end thereof, which is rotatably mounted on a stud 48 fast to the lever. Said roller engages with the rack 17 in a manner to swing the rack on supporting studs 49, and thereby disengage it from the pinion 16. The support 40 may be secured to the base-board by means of a nut 50.

Sometimes it is desirable to line-space the work-sheet one or more lines without returning the carriage. In this invention advantage is taken of the fact that the carriage is returned by means of the line-space lever 31 which is also effective to rotate the platen. According to this feature of the invention, it is proposed to lock the carriage upon depression of a space-bar 51. Said space-bar is fast to a pivotally mounted shaft 52, which carries an arm 53 fast thereto, said arm carrying at the end thereof a link 54, which is slidably mounted at its rear end upon a stud 55. Said link 54 extends upwardly at 56 and engages a locking pawl 57, which is forced in the path of teeth 58 of the escapement wheel 15, as shown in Figure 3, to thereby prevent rotation thereof. Said pawl is pivotally mounted upon a pin 59 fast to a bracket 60 and is normally held in its ineffective position, as shown in Figures 1 and 2, by means of a spring 61. The bracket may be secured to the track 19.

To soften the noise arising from the operation of the machine, the same is enclosed by a sheet-metal wall 62, which is fast to the base-board by means of screws 63. The wall is lined with sound-deadening material 64, the rear wall being in turn lined with a sheet-metal plate 65 to prevent the trailing edge of the work-sheet from engaging the rough surface of the sound-deadening material. Said plate is preferably curled at the bottom thereof to form a pocket as shown in Figure 5. The machine is enclosed at the top thereof by a cover 66 pivotally mounted on hinges 67. Said cover has an opening 68 sealed with a glass panel 69 to render the machine visible from the outside of the casing and to prevent the emission of sound through the opening. The cover may be also lined with sound-deadening material 70.

In order to facilitate the insertion and the removal of the machine from the casing, there is provided a front plate 71 which is secured to the front wall of the casing by means of wing-nuts 72. The cord is easily attached to the extension 32 of the line-spacing lever by means of a ball 73 fast to the end of the cord 30. Said ball is passed through a hole 74 and is locked in place by sliding the cord into a slot 75.

The machine may be secured to the base-board 25 by means of screws in the usual manner. In order, however, that the base-board may not be vibrated by the noise ensuing from operating the machine, there may be provided a felt pad 76 secured to the base-board and having depressions for receiving feet 77 of the machine.

It will be understood that in order to line-space the work-sheet while the cover is closed but without returning the carriage, the same is locked by holding down the space-bar 51, which throws the locking pawl 57 in the path of the teeth 58 of the wheel 15 to prevent rotation thereof. While the space-bar is held down, the handle 21 may be vibrated to rotate the platen repeatedly.

The carriage is normally held stationary by means of pawl 78 pivoted on stud 59. The pawl detains escapement-wheel 15, which is rotatable by spring-drum 79 connected thereto by tape 80. The escapement-mechanism described in the application of W. A. Dobson, No. 63,370, filed October 19, 1925, is illustrated.

Variations may be resorted to within the scope of the invention, and portions of the improvements may be used without others.

Having thus described my invention, I claim:

1. A sound-deadening casing for a type-writing machine having a carriage, escapement mechanism therefor, a platen, a line-spacing lever therefor, means for simultaneously line-spacing and returning the car-

riage, and means for locking the carriage from the outside of the casing in a manner to prevent the sliding movement of the carriage upon operation of the line-spacing means.

2. In a sound-deadening casing for a typewriting machine, the casing having a body part and a cover therefor, the typewriting machine having a carriage, a platen and a line-spacing mechanism therefor, means for line-spacing the platen, said means including a carriage-locking mechanism controlled by the spacing bar of the typewriting machine, and means for operatively connecting the line-spacing mechanism with a handle protruding to the exterior of the casing.

3. Means for line-spacing the platen of a typewriter in a sound-deadening casing, said means including, in combination, means controlled by the space-bar of the typewriter for locking the carriage, and means controlled by a carriage-return lever for actuating the line-spacing lever of the typewriter.

4. In a sound-deadening casing for a typewriting machine, the casing having a body part and a cover therefor, the typewriting machine having a carriage, a platen and a line-spacing mechanism therefor, means for line-spacing the platen, said means including a carriage-locking mechanism controlled by the spacing bar of the typewriting machine, means for operatively connecting the line-spacing mechanism with a handle protruding to the exterior of the casing, said last-mentioned means including a revolubly mounted drum having a cord wound therearound, one end of the cord being fast to the drum, the other end of the cord being fast to the line-spacing mechanism, and means controlled by said handle for rotating the drum.

5. Means for releasing the carriage of a typewriter in a sound-deadening casing, the typewriter having a letter-spacing rack and a letter-spacing wheel therefor; said means including a depressible button collapsibly mounted on the wall of the casing, a bell-crank controlled by said button, and a link for operatively connecting said bell-crank with a rocking arm pivotally mounted on a fixed support, said rocking arm having a roller at one end thereof, said roller being effective to swing the rack out of engagement with its associated gear.

6. A sound-deadening casing for a typewriting machine having a carriage, a revoluble platen, a line-space lever therefor, and a letter-spacing mechanism including a space-bar, the casing completely enclosing the machine except for the keyboard, means for returning the carriage from the outside of the casing, and means associated with the letter-spacing mechanism and controlled

by the space-bar for locking the carriage and preventing its displacement to thereby permit the line-spacing of the platen upon operation of the carriage-returning means.

7. In a sound-deadening casing for a typewriting machine, said casing completely enclosing the typewriting machine except for the keyboard, the typewriting machine having a carriage, an escapement mechanism therefor, a platen and a line-spacing lever therefor, means outside of the casing for simultaneously line-spacing the platen and for returning the carriage, said means being operatively connected to the line-spacing lever, and means for locking the carriage to thereby permit the line-spacing movement of the lever while preventing the return of the carriage.

8. In a sound-deadening casing for a typewriting machine, said casing completely enclosing the typewriting machine except for the keyboard, the typewriting machine having a carriage, an escapement mechanism therefor, a platen and a line-spacing lever therefor, means outside of the casing for simultaneously line-spacing the platen and for returning the carriage, said means being operatively connected to the line-spacing lever, and means for locking the carriage to thereby permit the line-spacing movement of the lever while preventing the return of the carriage, said last-mentioned means including a locking pawl controlled by the space-bar of the typewriting machine, said locking pawl interposing the teeth of the escapement wheel of the typewriting machine upon depression of the space-bar to thereby prevent rotation of the wheel.

9. In a sound-deadening casing for a typewriting machine, said casing completely enclosing the typewriting machine except for the keyboard, the typewriting machine having a carriage, an escapement mechanism therefor, including a pinion co-operating with a rack pivotally mounted on the carriage, a platen and a line-spacing lever therefor, means outside of the casing for positioning the carriage, said means including a carriage-return handle operatively connected to the line-spacing lever, and means for releasing the carriage, said last-mentioned means including a manual control outside the casing at one side of the keyboard and linkage for operatively connecting said control with the escapement mechanism in a manner to disconnect the latter from the carriage by swinging the rack rearwardly on its pivot out of engagement with the pinion by rearward pressure thereon, thereby permitting accurate positioning of the platen without opening the casing.

10. In a sound-deadening casing for a typewriting machine having a carriage and an escapement mechanism therefor, the es-

capement mechanism including an escapement wheel having a pinion associated therewith, the carriage having a rack arranged for engagement with said pinion, said rack being resiliently held in its effective position in engagement with the pinion, means mounted forwardly of the rack for contact therewith for rendering said rack ineffective, and means located externally of said casing and operatively connected to said means for controlling the same.

11. In a sound-deadening casing for a typewriting machine having a carriage and an escapement mechanism therefor, the escapement mechanism including an escapement wheel having a pinion associated therewith, the carriage having a rack arranged for engagement with said pinion, said rack being resiliently held in its effective position in engagement with the pinion, means controlled by a depressible button, located externally of said casing, for rendering said rack ineffective, said means including, in addition to said button, a bell-crank operatively connected thereto, and a link for operatively connecting said bell-crank to a fixed rocking arm contacting with said rack in a manner to push the rack out of engagement with the pinion upon depression of the button.

12. In a sound-deadening casing for a typewriting machine having a carriage and an escapement mechanism therefor, the escapement mechanism including an escapement wheel having a pinion associated therewith, the carriage having a rack arranged for engagement with said pinion, said rack being resiliently held in its effective position in engagement with the pinion, means controlled by a depressible button, located externally of said casing, for rendering said rack ineffective, said means including, in addition to said button, a bell-crank oper-

atively connected thereto, and a link for operatively connecting said bell-crank to a fixed rocking arm having a roller at one end thereof, the roller contacting with the rack in a manner to swing it out of engagement with the pinion and to hold it in its ineffective position for the full length of travel of the carriage.

13. A typewriting machine having a carriage, a platen, letter-spacing mechanism for said platen, a space-bar, and means operated upon the depression of said space-bar for locking said letter-spacing mechanism against yielding to the right.

14. A typewriting machine having a carriage, a platen, letter-spacing mechanism for said platen including an escapement-wheel, a space-bar, and means for locking said letter-spacing mechanism upon depression of said space-bar, including a dog mounted on the machine-frame and movable to engage said escapement-wheel, and an operative connection between said dog and said space-bar.

15. In a typewriting machine having a sound-deadening casing completely enclosing the same except the keyboard-extension thereof, said typewriting machine having a carriage, a platen and letter-spacing mechanism therefor, including a rack, and a carriage-return lever, the combination of means for releasing said carriage from said letter-spacing mechanism, means for returning said carriage, and independently-operable control means for said carriage releasing and returning means located outside of said casing and operating through said releasing and returning means, respectively, upon said rack and upon said carriage-return lever to permit accurate positioning of the platen with respect to the printing point of the machine without opening the casing.

EDWARD G. ROWLEY.
